U.S. Cl. D59—2

FIG. 1.

FIG. 2.

FIG. 3.

FIG. 4.

FIG. 1 is a schematic plan view of paper toweling showing my new design, a full width of the design being shown with the design unit repeating in regular succession to an indeterminate length, the dash lines being serrations;

FIG. 2 is an enlarged fragmentary plan view thereof showing the portion on the left of FIG. 1, the background configuration of the paper toweling is shown at the lower left corner, the remainder of the background having been omitted for convenience of illustration;

FIG. 3 is an enlarged fragmentary plan view showing the portions in the center of FIG. 1; and

FIG. 4 is an enlarged plan view showing the portion on the right of FIG. 1.

The drawing has been lined for color.

I claim:

The ornamental design for paper toweling, as shown and described.
